GRAVURE PRINTING PRESS

Christen R. Kaddeland, Shelton, Conn., assignor
to Harris-Seybold-Potter Company, Cleveland,
Ohio, a corporation of Delaware

Application June 30, 1933, Serial No. 678,431

29 Claims. (Cl. 101—157)

My invention relates to improved methods in rotary gravure printing and improved rotary gravure presses using intaglio printing cylinders, and more particularly to new and useful improvements in the inking methods and mechanisms for applying liquid ink in a solid stream to the printing-cylinder.

The objects of my invention are, among other things, to attain a complete and effective inking 10 of the design on the printing cylinder, and, in certain aspects, my invention is particularly adapted for using the quick-drying inks now used in very rapid rotary gravure printing.

According to my invention, I provide a completely confined body of ink that is maintained 15 under pressure against the intaglio printing cylinder, preferably in a relatively narrow solid stream throughout the length of the cylinder, thereby holding the ink out of contact with the 20 atmosphere until applied to the design on the cylinder.

Hence I am able through my invention completely to prevent any substantial evaporation 25 of these highly volatile inks, since such body of ink is applied to the printing cylinder very close to the impression or printing line of this cylinder, and the inked design thereon is almost immediately printed on the paper without allowing the 30 highly volatile ink to dry on such printing cylinder.

According to my invention, this ink is forced 35 to flow outwardly in a solid volume or stream from the confined body of ink, more or less in circulation, under pressure along the surface of the 40 design on the printing cylinder so as to dissolve and wash away any dried ink or other objectionable foreign matter adhering to this design to the end that a clean and freshly inked design is almost immediately presented at the printing line of the paper.

My invention is adapted for use in many types 45 of rotary gravure presses, and may be used, for example, in those web gravure presses of the type disclosed in my application for U. S. Letters Patent filed May 20, 1933, Serial No. 671,992, now patented, Number 2,064,168, dated Dec. 15, 1936, which embodies, among other things, a novel and simplified type of rotary printing-press in which the intaglio printing cylinder of a printing unit is rotatable in either direction through a reversible clutch drive, the press frames being shaped to permit the printing cylinder to be readily installed in, or removed from, the press from either end of the printing unit, whereby an exchange of printing cylinders may

be made which is an important advantage in rotary gravure presses.

Further objects of my invention are, among other things, to provide a new and improved form of ink distribution system for the intaglio cylinders that may be arranged as desired on either side of the printing cylinder depending on the direction of cylinder rotation as well as above or below the lateral diameter of such cylinder whenever required.

A further object is to provide improved mechanism for forcing the volatile liquid ink under pressure against the etched surface of the revolving printing-cylinder together with means for maintaining pressure for the ink impinging 15 against the etched surface, while embodying improved devices to remove the surplus ink and return same to the source of supply for preservation and re-use.

A further object of my invention is to provide 20 an improved ink distribution for gravure printing presses by which the volatile liquid ink will be distributed over the rotating intaglio printing cylinder without permitting any of the ink to escape during the inking process, except that 25 required to fill the ink wells in this cylinder which represent the image to be printed. My improved device is also built in such manner as to eliminate the necessity of enclosing the printing cylinder within the inking device as has hereto- 30 fore been the case.

A further object of my invention is to provide 35 a novel inking distribution system that is readily adjustable to printing cylinders of different sizes, which inking system may be placed in any desired position about the cylinder, and further may be permitted to be reversed to suit the direction of rotation of the printing cylinder. This novel construction also includes mounting of the reciprocating doctor blade or knife so 40 that the pressure of this doctor blade or knife against the printing cylinder may be varied transversely across the press to insure perfect removal of the surplus ink without injuring or defacing the engraved surfaces of such cylinder. 45

A further feature of my invention is the provision of a novel form of doctor blade mechanism for use in my shiftable ink distribution system by which the doctor blade or blades may be readily moved away from the printing cylinder 50 when an exchange of printing cylinders is to be made, coupled with improved mechanism for imparting the usual reciprocating movement of the doctor blade across the etched surface of the revolving cylinder whereby a uniform and

even movement is given to this doctor blade in all parts of its successive cycles.

A further feature of my invention is a novel form for the ink fountain which comprises an inner pressure chamber closely adjacent to the periphery of the printing cylinder, which pressure chamber has a comparatively narrow aperture so as to permit the ink to escape in all four directions against the cylinder surface so that any residue on the cylinder may be washed away by the passage of fresh ink. The surplus ink flows into a normal pressure return chamber surrounding the pressure chamber, from which return chamber the surplus ink is conveyed to the supply reservoir in which the ink is agitated and mixed with the fresh ink supply, and by means of a pump forced back into the pressure chamber, thereby making a complete circulating system in which the solid matters and liquid solvent are constantly kept in solution.

Further objects and advantages will appear hereinafter and be particularly pointed out in the appended claims, and the drawings show a preferred embodiment of my invention as applied to a web gravure printing-press such as is shown and described in my said co-pending application Serial No. 671,992, in which my improved ink distribution system herein disclosed is particularly adapted for use. However, my improvements are not necessarily limited to any particular form or type of gravure printing-press construction.

In the drawings,

Fig. 1 is an elevation of the lower portion of a web gravure press looking from the right in Fig. 3 and embodying my improvements as positioned on the intaglio printing cylinder, certain parts being shown in vertical section;

Fig. 2 is an end elevation of the ink reservoir and associated devices, partly in section, and located outside the press frames to the left of Fig. 1;

Fig. 3 is a side elevation of the press and ink reservoir with the ink fountain shown in dotted lines and looking from left of Figs. 1 and 2;

Fig. 4 is an enlarged vertical section of the ink fountain and doctor blade with associated devices arranged in contact with the printing cylinder that are shown in dotted lines in Fig. 3;

Fig. 5 is an elevation view looking from the right of Fig. 4;

Fig. 6 is a sectional detail view of the line 6—6 of Fig. 4;

Fig. 7 is an enlarged section on the line 7—7 of Fig. 6;

Fig. 8 is a detail view on the line 8—8 of Fig. 4;

Fig. 9 is a detail side view showing the guide bracket for the ink fountain and mechanism for reciprocating the doctor blade;

Fig. 10 is an enlarged section of the doctor blade and associated devices also shown in Fig. 4;

Fig. 11 is a sectional view, similar to Fig. 4, showing the undershot ink fountain and doctor blade when located on the under sides of the intaglio printing cylinder;

Fig. 12 is a diagrammatic lay-out of the different positions for the ink fountains in relation to the printing cylinder that may be rotated in either direction as indicated by the arrows;

Fig. 13 is a detail sectional view taken on the line 13—13 of Fig. 11; and

Fig. 14 is a detail elevation looking from the right of Fig. 11 when the printing cylinder is removed.

Similar numerals refer to similar parts throughout the several figures.

Referring to the drawings and more particularly to Figs 1 and 3, the press frames 15 and 16 are mounted on the base 17 in spaced-apart relation to afford sufficient space for the cylinders of the printing unit and their respective shafts which are preferably removable and adjustable in the press frames 15 and 16, as more particularly set forth in my pending application for patent Serial No. 671,992 hereinbefore mentioned.

The web gravure printing-press proper comprises the printing cylinder 18 having its shaft 19 journaled in the press frames 15 and 16 (Fig. 1), the therewith coating rubber cylinder 20 and the pressure cylinder 21 of the usual construction and mounting (Fig. 3). The web W is also shown in Fig. 3 in printing relation with the cylinders 18 and 20.

The printing cylinder shaft 19 carries outside the press frame 16 the coupling member 22 which is releasably engaged by the pins 23 pinned to the coupling member 24 slidably secured to the short shaft 25 journaled in the standard 26 as shown to the left in Fig. 1. The shaft 25 carries the bevel gear 27 that is driven by the bevel gear 28 fastened to the power shaft 29 that is rotated by any suitable source of power (not shown) in either direction (Fig. 12), as more particularly set forth in my said application for patent Serial No. 671,992.

Pinned to the insides of the press frames 15 and 16 (Fig. 1) are the swinging arms 30 and 31 respectively which carry at their upper ends my improved form of ink fountain and associated devices. These arms 30 and 31 are adapted to swing over the perpendicular (Fig. 3), so as to position the ink fountain on either side of the printing cylinder 18 as shown in the upper part 40 of Fig. 12 depending upon the direction of rotation of the printing cylinder 18.

The arms 30 and 31 are held in proper angular position to secure radial adjustment of the ink fountain for cylinders of different sizes by 45 latch pins 32 that engage suitable holes drilled in the press frames 15 and 16 to make the proper adjustments.

Means are provided for adjustably mounting the ink fountain and associated devices on the 50 swinging arms 30 and 31 to accommodate for printing cylinders 18 having variable diameters which are best shown in Figs. 1, 3 and 9: Such devices are duplicated on the press frames 15 and 16, and a description of one set will suffice 55 for both. Taking the swinging arm 30 (to the left in Fig. 1), the guide bracket 33 which supports the ink fountain is sleeved on the arm 30 which carries on its upper end the apertured lug 34 through which passes the screw-bolt 35 having its upper end 36 squared for a wrench. This screw-bolt 35 passes through the interiorly threaded lug 37 on the upper end of the guide bracket 33, while the lower end of the guide bracket 33 carries the collar 38 that slides on the 65 arm 31. By this mechanism the guide bracket 33 may be raised or lowered on the arm 30 to make adjustments of the position of the ink fountain and associated devices relatively to the printing cylinder 18 and such bracket 33 is held 70 in position on the arm 30 by the set-screw 39 (Figs. 3 and 9).

Pinned to the collars 38 on either side of the press inside the press frames 15 and 16 (Figs. 1 and 9) is the flat cross-plate 40 that supports 75

the ink fountain and associated devices that are best shown in Figs. 1, 3, 4 and 9: Mounted on the plate 40 is the ink fountain proper comprising an irregularly shaped casting 41 having the 5 end walls 42 and 43 (Figs. 1, 6 and 7), which carry the wedge-shaped ink pressure chamber 44 formed in the casting 45 with the top plate 46 and under plate 47 to form an elongated narrow orifice 48 through which the ink under pressure is forced against, and impinges on, the cylinder 18 as shown more particularly in Figs. 4 and 6.

The spacing blocks 49 secure the pressure chamber 44 to the fountain casting 41 fastened to the support plate 40 which also carries a flexible plate 95 adapted to rest against the periphery of the cylinder 18.

The end walls 42 and 43 are fastened and sealed to the fountain casting 41 and support plate 40 in such manner as to leave a space between the 20 closed ends of the pressure chamber 44 and these end walls 42 and 43, and also allow the ends of the printing cylinder 18 to project beyond the end walls 42 and 43. The end walls 42 and 43 are also formed so as to support the ends of the 25 L-shaped doctor blade bar 113 with the doctor blade 94 and supporting plate 118, and are provided with a U-shaped packing 54 held in contact with the cylinder 18 (Figs. 4, 6 and 7) by means of the flexible spring 53 arranged within 30 the elongated socket 50 and secured by means of clamp screw 51 and washer 52 to the end walls 42 and 43.

The resiliency of the packing 54 and spring 53 compensates for cylinders of various sizes, a 35 small cylinder 18 being shown in dot and dash lines in Fig. 7. This construction affords a substantially air-tight receiving chamber surrounding the pressure chamber 44, the upper portion being indicated at 96, while the lower portion of 40 this receiving chamber is indicated at 97.

Means are provided for forcing the liquid ink under pressure from the source of supply through the pressure chamber 44 against the etched or engraved surface of the printing cylinder 18, combined with means to return the surplus ink removed from such surface by the doctor blade mechanism to the source of supply for preservation and re-use, all of which is best shown in Figs. 1-6; Outside the press frame 15 is the ink 45 supply reservoir 55 mounted on the legs 56 and is provided with the inlet 57 and cap 58 through which the ink is poured into the reservoir 55 when the cap 58 is removed. Centrally mounted within the reservoir 55 is the rotary shaft 59 50 driven by the sprockets 60 around which passes the chain 61 actuated by the sprocket 63 mounted on the shaft 64 of the motor 65 fastened to the top of the side-wall 66 of the reservoir 55 (Fig. 2).

Fastened to the shaft 59 near the bottom of the 55 reservoir 55 are a pair of stirrers 67 that agitate the ink to maintain a uniform consistency in solution before the ink passes through the circular opening 68 in the bottom 69 of the reservoir which supports the rotary centrifugal pump casting 70. The pump proper is composed of the 60 rotary member 71 fastened to the lower portion of the shaft 59 by the cross pin 72. The end of the shaft 59 revolves in the socket bearing 73 in the casting 70.

The member 71 has formed therein a plurality of outwardly flaring passages 74 (two being shown in Fig. 2), through which the ink is drawn from the reservoir 55 as indicated by the arrows and forced under pressure against the sidewalls 75 of the casting 70 into the circular chamber 75

from which the ink under pressure passes through the pipe 76 to the pressure chamber 77 formed in the casting 78 that is supported on the base 79 between the press frames 15 and 16.

Pivoted mounted to the casting 78 on the hollow roller 80 is the rocking pipe casting 81 having the circular chamber 82 that registers with the pressure chamber 77. This chamber 82 communicates with the pipe 83 fastened to the top of the casting 81 and the smaller pipe 84 is 10 adjustably telescoped within the pipe 83 where it is held against leakage by the stuffing-box 85. As shown in Figs. 1 and 3, the upper end of the pipe 84 is connected with the chamber 86 formed in the casting 87 rotatably pivoted on the hollow 15 roller 88 to the casting 89 fastened by screws 90 to the ink fountain casting 41 and the cross bar 91 secured to the ink fountain end walls 42 and 43 (Fig. 1). The chamber 86 communicates with the chamber 92 formed in the casting 89, which 20 chamber 92 is connected by the pipe 93 to the inner pressure chamber 44 to force the liquid ink against the periphery of the cylinder 18 throughout its width which is less than the distance between the end walls 42 and 43 that carry felt pads 25 54 as shown more particularly in Figs. 4 and 6. The arrows in Figs. 2, 3 and 4 indicate the path of the ink forced under pressure from the bottom of the reservoir 55 to the cylinder 18.

The liquid ink that is forced against the cylinder 18 forms a closed ink-circulating system due to the highly volatile nature of the solvent used in the manufacture of the ink. Such solvent always forms sufficient vapor to replace, in fact more than replace, the volume of liquid ink 35 carried out of the closed system by the revolving printing-cylinder 18, so that the space within the system not occupied by the liquid ink is completely filled by the saturated solvent vapor. Such closed system for the circulating ink is one 40 of the advantages of my invention in that the escape of such highly-explosive saturated vapor is prevented. Even with the use of a non-vaporizing liquid printing ink, any vacuum caused by withdrawal of such ink would not interfere with 45 the proper coating of the cylinder 18, since in printing practice the circulating system, and more particularly the reservoir 55, is never completely filled with the ink.

Referring again to Figs. 2-4, the surplus ink 50 after issuing from the elongated orifice 48 in all four directions under pressure is removed from the etched surface of the cylinder 18 by the reciprocating doctor blade 94 and passes into the receiving chambers 96 and 97 above and below the 55 pressure chamber 44 and then through the passages 98 into the chamber 99 that is connected by the outlet pipe 100 with the circular chamber 101 formed in the casting 89 that communicates with the circular chamber 102 in the casting 87 60 (Fig. 1).

From the chamber 102 the surplus ink is conveyed by the pipe 103 adjustably telescoped within the pipe 104 to the outlet chamber 105 in the casting 81. The stuffing-box 106 on the upper 65 end of the pipe 104 prevents any leakage of ink from the two pipes 103 and 104. From the chamber 105 the surplus ink passes into the chamber 107 in the casting 78, and thence through the interconnected pipes 108, 109 and 70 110 into the suction pump 110^A secured to the reservoir 55, such pump being driven by means of the chain 61 through the sprocket 62 and shaft 110^B. This suction pump 110^A is used to discharge the surplus ink through the pipe 111 into 75

the upper part of the reservoir 55 above the strainer 112 (Figs. 1-3). The arrows in Figs. 1-4 show the path of the surplus ink flowing under normal pressure from the surface of the cylinder 18 back into the reservoir 55 where it is preserved for re-use under forced pressure by the devices hereinbefore described.

The reciprocating doctor blade construction with associated devices for adjusting and holding the edge of the doctor blade 94 with the required pressure on the peripheral surface of the printing cylinder 18 is best shown in Figs. 1, 4-6, 8 and 10: The slideable L-shaped bar 113 extends across the press, and rests on the casting 41 (Fig. 4) and end walls 42 and 43 (Figs. 6 and 7); this bar 113 has a series of slots 114 (four being shown in Fig. 1) through which the screw-bolts 115 pass and are tapped into the casting 41 (Fig. 4). The washers 116 are placed between the heads of the bolts 115 and the elongated top surfaces of the slots 114 and are held in position by spacers 117.

At the forward end of the bar 113 (Figs. 4 and 10) is the transverse plate 118 held in position by the key 119 to which the doctor blade 94, spacer 120 and doctor reenforcing blade 121 are fastened by the clamping plate 122 which is held to the plate 118 by a series of screw-bolts 123 (only one being shown in Figs. 4 and 10), that are tapped into the plate 118.

At convenient intervals the two adjacent plates 118 and 122 have interiorly threaded sockets 124 into which adjusting screws 125 are fitted, the forward ends of the screws 125 bearing against the rear edge of the doctor blade 94 to adjust the position of the doctor blade 94 with reference to the plate 118.

To removably hold the doctor blade 94 and the several clamping plates in position on the bar 113, I have provided a special form of clamping device best shown in Figs. 1, 2, 4 and 5: Extending lengthwise of the ink fountain is the transverse bar 137 adapted to impinge against the doctor blade clamping plate 122. This bar 137 is fastened to the lugs 136 integral with a series of arms 132 by the screws 138.

The arms 132 have trunnions 127 journaled in the brackets 128 which are fastened to the slideable bar 113. Journaled in the upper portion of the brackets 128 are the cross pins 129 to which the clamp bolt 130 is fastened, this bolt 130 being screw threaded at its outer end to carry the knurled nut 134 adapted to abut against the outer face of the U-shaped lugs 133 on the left sides of the arms 132 (Fig. 5). The tightening of the nuts 134 will cause the arms 132 and bar 137 to pivot about the trunnions 127 so that the downwardly-projecting nose 139 on the bar 137 will lock the doctor blade 94 with associated plates in position on the sliding bar 113.

Conversely when this nut 134 is loosened so as to permit it and the bolt 130 to drop down to the position shown in dot and dash lines in Fig. 4, the bar 137 and associated arms 132 are free, and may be swung upwardly to the right (Fig. 4), and thus leave the doctor blade 94 with associated plates shown in Fig. 10 free and removable.

Referring more particularly to Figs. 4, 5 and 8, the bar 137 is formed with a series of spaced-apart lugs 140 having their under sides rounded out to receive the cross-rod 141 secured by screws 143 on the rod 141 between the lugs 140. A series of rock-levers 142 are carried on the rod 141, such levers being located in the spaced openings 144 between the series of lugs 140 (Fig. 5). The forward end 145 of the levers 142 are adapt-

ed to bear upon the spring pressure blade 121 (Figs. 4 and 10) throughout the length of the doctor blade 94, while the upper arms 146 are engaged by the slideable pins 147 (Figs. 1, 4 and 5) fitted within the holes 148 drilled in the bar 137. Enclosed within the holes 148 are a series of compression springs 150, the forward ends of which bear against the rear ends of the pin 147 while the rear ends of the springs 150 are engaged by the tips of the adjusting screw-bolts 151 threaded into the rear ends of the holes 148. By this mechanism a delicate pressure adjustment may be yieldingly made upon the doctor blade 94 throughout its width, by advancing or retracting the screw-bolts 151, the springs 150 imparting a variable yielding pressure through the pins 147 and rock levers 142 on the forward margin of the pressure blade 121 that bears on the doctor blade 94 throughout its width (Figs. 4, 5 and 10).

Means are provided for reciprocating the doctor blade 94 with an even uniform speed in all parts of its successive cycles that are best shown in Figs. 1 and 9: The doctor blade carrying slide-bar 113 has pivoted thereto the cam-roller 152 that engages the grooved cam 153 of special formation to impart a uniform movement to the bar 113, which cam 153 is mounted on the short shaft 154 journaled in a pair of bracket bearings 155 secured within the cam casing 156 that is fastened to the casting 41 by any suitable means.

The shaft 154 carries the worm gear 157 that is actuated by the worm 158 fastened to the stub-shaft 159 journaled in the cam casing 156 (Fig. 9). The lower end of the shaft 159 carries universal joint member 160 to which is pivoted the shaft 161 within which is telescoped the shaft 162 which through the slideable coupling 163 causes the shaft 161 to be rotated in any position depending on the relative positions of the ink fountain and associated devices on the arms 30 and 31.

The shaft 162 is pivotally connected by the universal joint member 164 to the shaft 165 that has keyed thereto the bevel gear 166. The bevel gear 166 is journaled in the bearing 167 on the standard 168 that is supported on the base 17. The bevel gear 166 meshes with the bevel gear 169 fastened to the end of the horizontal drive shaft 170 that is journaled in the standards 26 and 168 (Fig. 1). The outer end of the shaft 170 carries the gear 171 that is driven by the idler gear 172 which in turn is driven by the gear 173 secured to the shaft 25 which is driven from the power shaft 28 as hereinbefore described.

In Figs. 11-14, I have shown a modified form of my invention in which the doctor blade is located below the pressure chambers, which modification is substantially similar to that shown in Figs. 1-10 which has been hereinbefore described except that it is arranged to provide drainage of the surplus ink. Fig. 12 shows the different positions for the fountain and doctor blade on either side of the printing cylinder dependent upon the direction of rotation of such cylinder. In describing the construction shown in Figs. 11-14, the same reference numerals will be used to identify similar parts in the Figs. 1-10 construction, so far as possible.

Referring to Figs. 11, 13 and 14, to the irregularly shaped casting 41 are fastened the same end walls 42 and 43, and the casting 41 is also similarly mounted between the press frames 15 and 16. The forward end of the inner press-

sure chamber 174 for the ink under pressure from the pump 70 is formed by the bar 174^a and plates 177 and 178 all within the casting 41, and the ink flows into the chamber 174 from the pipe 93 (not shown in Fig. 11), and through the ports 175 (Figs. 11, 13 and 14) into the elongated orifice 176 formed between the thin plates 177 and 178 fastened in the casting 41, the liquid ink being under pressure during its travel into the orifice 176.

The outer end edges of the plates 177 and 178 extend in close proximity to the peripheral surface of the cylinder 18 (a small cylinder being indicated by dot and dash lines in Fig. 11).

The top plate 179 is fastened to the inclined surface 180 of the casting 41 to form the chambers 181 to collect surplus ink above the plate 177 and return same through the channels 182 to the chamber 183 and thence through the port 184 to the outlet pipe 100. The surplus ink removed by the undershot doctor blade 94 passes above the plate 178 through the series of channels 182 (Figs. 13 and 14) into the chambers 183 and then through the port 184 to the outlet pipe 100. The arrows in Figs. 11, 13 and 14 indicate the direction of ink flow in this construction.

The doctor blade slidable bar 113 is held to the casting 41 by the series of screw-bolts 115 that pass through slots 114 and are tapped into the casting 41 in the same ways as in the Figs. 1-10 construction. However, I have provided compression springs 185 coiled about the bolts 115 between their heads and the washers 116 to afford a yielding attachment to the casting 41. Also pivoted on the trunnions 127 is the clamping bar 137 that holds the doctor blade mechanism in position on the bar 113, which bar 137 is removably held in position by the screw-bolts 130 fastened into the cross-pin 129 with the bolts 130 maintained within the lugs 133 by the nuts 134 as in the Figs. 1-10 construction. The devices for holding and adjusting the position of the doctor blade 94, coupled with the mechanism for variably adjusting the pressure along the width of the doctor blade 94 are the same as the similar devices and mechanisms shown and described with reference to the Figs. 1-10 construction and need not again be described in connection with the structures shown in Figs. 11-14.

The several operations of the various different mechanisms and devices in my improved gravure press have already been described in conjunction with the separate descriptions of their structural details as embodied in the press.

However, the general operations may be summarized as follows: After the printing cylinder 18 has been installed in the press frames 15 and 16 with its driving coupling connections with the power shaft 29, the swinging arms 30 and 31 are located to suit the direction of cylinder rotation by means of the latchpins 32 that engage the press frames 15 and 16. Then the guide brackets 33 are raised or lowered on the arms 30 and 31 by the bolts 35 to accommodate for the size of the printing-cylinder 18. The ink fountain, particularly the elongated orifice in the pressure chamber 44, is then adjusted to the peripheral surface of the cylinder 18 approximately to the positions as shown in Fig. 4, with the nuts 134 holding the doctor blade 94 to the slidable bar 113 supported on the casting 41. Forward adjustment of the doctor blade 94 is made by the series of screw-bolts 125, and the required pressure is yieldingly imparted to the doctor blade 94 by the adjusting screw bolts 151

throughout the length of the doctor blade 94 as has been hereinbefore described.

When the ink fountain and doctor blade constructions carried by the cross-plate 40 that is fastened to the guide brackets 33 are brought into operative position, the slidable pipe connections through the telescoped pipes 83, 84 and 103, 104 are brought into position through the casting 81 rotating on the casting 18 and the casting 87 rotating on the casting 89 as has been heretofore described, the stuffing-boxes 85 and 106 permitting the pipe connections to be lengthened or shortened as required.

In like manner the shaft 154 with the cam 153 that reciprocates the doctor blade 94 is brought into position in setting up the ink fountain as set forth in the preceding paragraph, with the telescoped shafts 161 and 162 adjustable through the coupling 163 and deriving their revolutions from the shaft 170, the cam-roller 152 on the bar 113 imparting to the latter the reciprocatory movement for the doctor blade 94.

The liquid ink under pressure from the centrifugal pump in the casting 70 in the Figs. 1-10 construction is forced against the peripheral surface of the cylinder 18 through the elongated orifice 48 and then escapes in all four directions around the edges of the plate 46 and 47 forming the orifice 48 as shown in Figs. 4 and 6. Above the plate 46 the surplus ink is removed by the doctor blade 94; the ink issuing below the plate 47 is caught by the under blade 95; and both streams of surplus ink as shown by the arrows in Figs. 3 and 4 are collected in the chamber 99 and then returned to the reservoir 55 by the pipe 35 connections heretofore described.

In the modified Figs. 11-14 construction, the liquid ink under pressure from the pump is forced against the cylinder 18 through the elongated orifice 176, and escapes in all four directions around the thin plates 177 and 178 (Figs. 11 and 13). The surplus ink is collected by removal from the cylinder 18 by the top plate 179 and undershot doctor blade 94, and is then returned by the channels 182 into the chambers 183 from which it flows through the port 184 and the outlet pipe 100 to the pipe connections 45 that convey this ink back to the reservoir 55 as hereinbefore described. The arrows in Figs. 11 and 13 show the path of the liquid ink to and from the surface of the printing-cylinder 18.

Referring to Fig. 12, the cylinder 18 is shown as being rotated in either direction. When rotating in a clockwise direction, the ink fountains and associated doctor blade devices will be arranged as shown in dot and dash outline, while the full line positions of these devices show their respective positions when the cylinder 18 is revolving in an anti-clockwise direction.

It will be observed that a very delicate adjustment of pressure on the doctor blade 94 is obtained through the yielding control of the series of rock-levers 142 that bear on the spring pressure blade 121 which coacts with the front edge of the doctor blade 94 through manipulation of 65 the series of screw-bolts 151 extending across the press. This construction ensures perfect removal of the surplus ink from the cylinder 18 without injuring or defacing its engraved surface. Furthermore my improved press is built to 70 avoid any loss of ink through leakage by the devices shown more particularly in Figs. 6 and 7 with all surplus ink returned to the reservoir 55 for preservation and re-use.

Furthermore I maintain a body of ink under 75

pressure against the moving intaglio printing cylinder 18 with the body of ink preferably in contact with the design under pressure in a narrow solid stream longitudinally disposed along the cylinder surface to force the ink positively into the depressions of the design, with the surplus ink not taken by the design flowing away from body of ink under pressure, which surplus is then conveyed through a closed circulating system that includes the closed reservoir of ink 55 back to the body of ink that impinges in a continuous solid stream on the cylinder surface.

In the mechanisms shown I use devices forming an elongated orifice or slot extending the length of the cylinder 18 for supplying ink under pressure to the design on the cylinder. Such slotted member is positioned between the walls of the surrounding chamber that is also filled with ink, such member removing surplus ink from the cylinder, chiefly on both longitudinal sides of such slotted member. Hence the volume of ink in excess of that required for inking the cylinder is directed into the design not only to remove all dirt, ink residues and other foreign matter, but also to sweep out all air from the depressions in the design as well as to displace the film of air carried on the surface of the rapidly rotating cylinder 18.

My invention, in its broader aspects, is not limited to the particular construction and arrangement of the ink fountains, doctor blades and associated mechanisms including the pump and pipe connections as shown in the gravure printing-press illustrated in the drawings, since many changes may be made without departing from the main principles of the invention and without sacrificing its chief advantages in use. Furthermore my improvements may be embodied in gravure presses of various types where it is particularly desirable to secure delicate pressure adjustments for the removal of surplus ink as well as to secure the proper distribution of ink on the peripherally etched surfaces of the printing cylinders as well as to prevent any escape of surplus ink and volatile solvents used therein.

45 I claim as my invention:

1. In a gravure printing-press, a printing cylinder, a reciprocating doctor blade coacting with said cylinder, an independent yielding reenforcing member bearing on said blade, and means for variably and yieldingly exerting pressure on said reenforcing member on spaced-apart portions thereof throughout its length.

50 2. In a gravure printing-press, a printing cylinder, a reciprocating doctor blade coacting with said cylinder, an independent yielding reenforcing member bearing on said blade, and a series of spaced-apart spring-actuated rock-levers bearing on said reenforcing member for exerting independently-controlled yielding pressure 55 through spaced-apart portions of said reenforcing member in yielding contact on said doctor blade throughout its length while the press is in operation.

60 3. The method of rotary intaglio printing which comprises circulating ink through a system and maintaining a confined body of ink therefrom under pressure against a rotating printing cylinder to cleanse and ink the design thereon.

65 4. The method of rotary intaglio printing which comprises circulating ink through a closed system and maintaining a body of ink therefrom under constant pressure against a rotating printing cylinder to cleanse and ink the design thereon.

70 75 5. The method of rotary intaglio printing which

comprises circulating ink in a closed system including a reservoir of ink forcing a body of ink from said reservoir under constant pressure against the moving printing cylinder to cleanse and ink the design thereon, and returning surplus ink from the impact to the reservoir. 5

6. The method of rotary intaglio printing which comprises circulating ink in a closed system including a reservoir of ink, forcing a body of ink from said reservoir in a solid stream under constant pressure against the moving printing cylinder to cleanse and ink the design thereon, and returning surplus ink from the impact to the reservoir. 10

7. The method of rotary intaglio printing which comprises circulating ink in a closed system, including a reservoir of ink spaced apart from the printing cylinder, forcing a body of ink from said reservoir in a solid stream under constant pressure against the moving printing cylinder to cleanse and ink the designs thereon, and returning surplus ink from the impact to the reservoir. 15 20

8. The method of rotary intaglio printing which comprises maintaining a body of ink under constant pressure directly applied as a solid body against a rotating printing cylinder and longitudinally thereof to cleanse and ink the design thereon, and forcing surplus ink to escape only 25 at the outer edges of said body along and in contact with the cylinder surface. 30

9. In the method of inking a rotary intaglio cylinder, the step which consists in maintaining a confined body of ink in a flowing stream under pressure against the moving cylinder to cleanse and ink the design thereon while removing surplus ink therefrom at points spaced from said body in contact with the cylinder surface. 35

10. In the method of inking a rotary intaglio cylinder, the step which consists in maintaining a confined body of ink in a flowing stream under pressure against the moving cylinder to cleanse and ink the design thereon while removing surplus ink therefrom at points spaced from said body in contact with the cylinder surface and returning same to the body of ink. 40 45

11. In a gravure printing-press, a closed ink circulating system including means for maintaining a body of ink under constant pressure against a moving printing cylinder to cleanse and ink the design thereon, means for conveying surplus ink 50 away from the cylinder, and means for returning the surplus ink to said body under pressure.

12. In a rotary gravure printing-press, a closed ink reservoir, a closed pressure system for conveying ink from said reservoir under constant 55 pressure against a moving printing cylinder to cleanse and ink the design thereon and for thereafter returning the surplus ink to said reservoir.

13. In a rotary gravure printing-press, a closed ink reservoir, a closed system including means for conveying ink from the reservoir to a printing cylinder and maintaining a body of ink in a solid stream under constant pressure against the moving cylinder to cleanse and ink the design thereon, and means for returning surplus ink from said body under pressure to said reservoir. 60 65

14. An inking mechanism for a rotary gravure printing-press comprising an ink-confining member having a slot extending longitudinally of the printing cylinder and adjacent thereto, means for maintaining a body of ink in said slot under constant pressure to cleanse and ink the design on said cylinder, a doctor for removing ink from 70 75

- the surface of the cylinder, the doctor and one side of said member providing a passageway for ink flowing away from the cylinder.
15. An inking mechanism for a rotary gravure printing-press comprising an ink-confining member having a slot extending longitudinally of the printing cylinder and adjacent thereto through which slot ink under constant pressure is forced against the moving cylinder to cleanse and ink the design thereon, a slotted chamber directly adjacent to the first slot to convey surplus ink from said cylinder, and a doctor for wiping the surface of the cylinder.
16. An inking mechanism for a rotary gravure printing-press comprising an ink-confining member having a slot extending longitudinally of the printing cylinder and adjacent thereto, means for maintaining a body of ink in said slot under constant pressure to cleanse and ink the design on said cylinder, a doctor for removing ink from the surface of the cylinder, the doctor and one side of the member providing a passageway for the ink flowing away from the cylinder, the slot and said passageway being substantially coextensive.
17. An inking mechanism for a rotary gravure printing-press comprising an ink-confining member having a slot extending longitudinally of the printing cylinder, means for maintaining a body of ink in said slot under constant pressure to cleanse and ink the design on said cylinder, said slot being adjacent thereto for conveying surplus ink therefrom and a doctor for removing ink from the surface of the cylinder, the doctor forming one side of a slotted chamber directly adjacent to said slot.
18. In an inking mechanism for a rotary gravure printing-press, a chamber extending longitudinally of the printing cylinder and having an open side arranged against the cylinder, an ink supply member within the chamber having a slot extending longitudinally of the cylinder in substantially sealing contact therewith for maintaining a body of ink in said slot under constant pressure to cleanse and ink the design on said cylinder, said member being positioned to provide an outlet between it and the chamber, and means for supplying ink to the member.
19. In an inking mechanism for a rotary gravure printing-press, a chamber extending longitudinally of the printing cylinder and having an open side arranged against the cylinder, an ink supply member within the chamber having a slot extending longitudinally of the cylinder in substantially sealing contact therewith for maintaining a body of ink in said slot under constant pressure to cleanse and ink the design on said cylinder, said member being positioned within the chamber to provide outlets on either side of the member through which ink may flow from the cylinder.
20. In an inking mechanism for a rotary gravure printing-press, a chamber extending longitudinally of the printing cylinder and having an open side arranged against the cylinder, an ink supply member within the chamber having a slot extending longitudinally of the cylinder in substantially sealing contact therewith for maintaining a body of ink in said slot under constant pressure to cleanse and ink the design on said cylinder, said member being positioned to provide an outlet between it and the chamber, means for supplying ink to the member and a doctor for wiping the surface of the cylinder, the doctor forming a wall of the chamber.
21. In a printing-press, a printing cylinder rotatable in either direction, means for forcing liquid ink in a solid stream under pressure against the surface of said rotating cylinder, said means being arranged radially to said cylinder, said inking means being shiftable to either side of the vertical diameter of said cylinder.
22. In a printing-press, a printing cylinder rotatable in either direction, an ink distribution device for forcing liquid ink in a solid stream under pressure against the surface of said rotating cylinder, said device being arranged radially to said cylinder and to be adjustable for cylinders of different sizes, said device being shiftable to either side of the vertical diameter of said cylinder.
23. In a gravure printing-press, a printing cylinder, an inking mechanism therefor comprising a receiving chamber for surplus ink coating with a portion of said cylinder surface to form a seal, means for adjusting the position of said inking mechanism to accommodate for cylinders of different sizes while holding the sealing relation of said chamber in respect to the cylinder surfaces, said inking mechanism being shiftable to either side of the vertical diameter of said cylinder for different directions of rotation thereof.
24. An inking mechanism for a rotary gravure printing-press comprising an ink-confining member having a slot extending longitudinally of, and adjacent to, the printing cylinder, means for maintaining a body of ink in said slot under constant pressure to cleanse and ink the design on said cylinder, an outlet chamber adjoining said slot for conveying surplus ink from the cylinder surface, a doctor for removing ink from the cylinder, the doctor forming one side of said outlet chamber, and a pump and conduits for supplying ink to and carrying ink from the member.
25. An inking mechanism for a rotary gravure printing-press comprising an ink-confining member having a slot extending longitudinally of, and adjacent to, the printing cylinder, means for maintaining a body of ink in said slot under constant pressure to cleanse and ink the design on said cylinder, an outlet chamber adjoining said slot for conveying surplus ink from the cylinder surface, a doctor for removing ink from the cylinder, the doctor forming one side of said outlet chamber adjacent said slot, and a pump and conduits for supplying ink to and carrying ink from the member, said pump and conduits forming a closed pressure system for the circulation of ink.
26. In the method of inking a rotary intaglio cylinder, the steps which consist in maintaining a confined body of ink under constant pressure against the moving cylinder to cleanse and ink the design thereon while restricting the thickness of the ink film adhering to the cylinder, and thereafter removing the ink film from the peripheral surface of the cylinder at points spaced from said body of ink.
27. In the method of inking a rotary intaglio cylinder, the steps which consist in maintaining a confined body of ink under constant pressure against the moving cylinder to cleanse and ink the design thereon, while controlling the thickness of the ink film adhering to the cylinder, and thereafter removing the ink film from the peripheral surface of the cylinder at points spaced from said body of ink.
28. In a gravure printing-press, a closed ink circulating system including means for maintain-

ing a confined body of ink under constant pressure against a moving printing cylinder to cleanse and ink the design thereon, means associated with said last-mentioned means for restricting the thickness of the ink film adhering to said cylinder, and means for removing the ink film from the peripheral surface of the cylinder at points spaced from said body of ink.

29. In a gravure printing-press, a closed ink circulating system including means for main-

taining a confined body of ink under constant pressure against a moving printing cylinder to cleanse and ink the design thereon, means associated with said last-mentioned means for controlling the thickness of the ink film adhering to said cylinder, and means for removing the ink film from the peripheral surface of the cylinder at points spaced from said body of ink. 5

CHRISTEN R. KADDELAND. 10
